UNITED STATES PATENT OFFICE.

WILLIAM H. P. CREIGHTON, OF NEW ORLEANS, LOUISIANA.

EVAPORATOR.

1,424,992.

Specification of Letters Patent. Patented Aug. 8, 1922.

Application filed December 30, 1920. Serial No. 434,083.

To all whom it may concern:

Be it known that I, WILLIAM H. P. CREIGHTON, a citizen of the United States, residing at New Orleans, in the parish of 5 Orleans and State of Louisiana, have invented certain new and useful Improvements in Evaporators; and I do hereby declare the following to be a full, clear, and exact description of the invention, such as 10 will enable others skilled in the art to which it appertains to make and use the same.

The density of sugar and other juices or liquids is increased by successive boiling, usually at pressures below that of the atmosphere, in a series of vessels called, collectively, a multiple effect.

In a multiple effect the first vessel is supplied with steam from an external source, usually the exhaust from the main engines. 20 Economy is attained by using the steam which rises from the boiling liquid in the first heater or effect as the heating agent in the next heater or second effect. Similarly with the remaining vessels, the steam rising from 25 the boiling liquid in one effect serving to evaporate a further quantity of water from the liquid in the next succeeding effect.

To operate in this manner the vapor pressures on the liquid surfaces of the different effects must differ, the highest pressure being that on the surface of the liquid in the first effect. This difference of pressure in two adjacent effects is essential for the transfer of heat, and it also furnishes the 35 force to move the liquid from one effect to the next.

The density of the liquid is increased by partial evaporation in each effect; and the greatest density of the liquid is in the last 40 effect, from which the liquid is pumped, or carried off by gravity, in the usual way.

Standard vertical effects are divided into belts, the lowest, into which the liquid enters, is called the bottom belt; above it is 45 the steam belt which either receives steam from the engines or from the vapor belt of a preceding effect, and distributes it to the intertubular heating space. Above the steam belt, are the vapor belt, the dome and 50 the top.

The object of this invention is to increase the rate of evaporation per unit of heating surface in any effect or vacuum pan having vertical or inclined juice tubes between tube 55 sheets, by certain alterations in the design of the steam belt.

To secure the highest rate of heat transmission through heating surfaces, the most recent experiments show that, among other requirements, it is essential;

(1) To obtain the highest possible average velocity of both the heating and heated fluids past the heating surfaces;

(2) That the amount of incondensable gases must be kept to the irreducible minimum.

The design of evaporators now generally in use violates these requirements; as will be hereinafter shown:—

To better illustrate my invention I have 70 shown two effects connected together, the first of the present standard make now generally in use, and the second the same general type modified according to my invention.

Reference is had to the accompanying drawings, in which:—

Figure 1 is a diagrammatic view of two effects connected together, one of the old and the other of my improved construction, 80 parts being shown in central vertical section, and parts being omitted for the sake of clearness in the drawings;

Figure 2 shows a half sectional view along the line 2—2 of Figure 1, and looking in the 85 direction of the arrows; parts being omitted, and

Figure 3 shows a half sectional view along the line 3—3 of Figure 1, parts being omitted for the sake of clearness in the 90 drawings.

Like parts are indicated by similar reference symbols throughout the several views.

A represents an effect of the present standard make supplied with heating fluid 95 through the pipe B, and provided with the pipe B' for carrying off the vapor evaporated; this pipe B' is connected to the pipe B² as shown in dotted lines, whereby the vapor rising from the effect A is delivered 100 to the heating chamber of the effect A'; the vapor rising from the latter being carried off by the pipe B³ and delivered either to the succeeding effect in the series or to the condenser, not shown.

Each effect has its bottom belt G, its vapor belt I, its dome J, and its top N, which are, or may be, of standard make, and it is only with regard to the steam belt that my present invention relates. In the effect A, the 110 present well known construction of steam belt H and connections are shown, while in

the effect A', my improved form of steam belt H' is illustrated. Each steam belt is surrounded with an annular chamber h^o .

Referring first to the well known construction of the steam belt H, shown to the right of Fig. 1, the heating surface comprises a large number of vertical tubes h of small diameter secured in the tube sheets f' and f^o , in which tubes the liquid in boiling moves upwards, and of one central downcomer D, in which the liquid moves downwards or returns to the bottom belt. Steam after entering the belt at B passes to the right and left in the chamber h^o and enters the undivided intertubular space through the vertical openings, p' , p^2 , p^3 , etc. in the inner wall of the annular belt. Similar ports should be provided on the other side of the apparatus.

Much more steam enters the ports p' , directly opposite the pipe B, and p^2 , where the currents (moving in opposite directions) meet, than enters any intervening port on either side. Opposite each port, especially p' and p^2 , a few tubes receive a strong current of steam for their entire length. These tubes are especially efficient, at the expense of a much larger number of tubes not so favorably placed.

After the steam enters the intertubular space, its velocity is low and its direction fluctuating. The various currents moving radially from the ports interfere with one another, and so neutralize the velocity past the heating surfaces.

To be able to remove air or other incondensable gas, it is essential to accumulate it in one spot continuously. With the ever varying and uncertain movement of the steam in the undivided intertubular space, this is not possible. Hence there is much guess work in the positioning of a pipe R, perforated in the steam belt and connecting to the vapor belt. By partially opening a valve X, the incondensable gases and some vapor are supposed to pass into the vapor belt due to the lower pressure therein.

It will be of course understood that the water of condensation will be drawn off from the steam belt H, but there are various ways well known in the art for accomplishing this result, and the said feature not being a part of my present invention is not shown therein.

In the effect A', shown to the left of Fig. 1, the heating surface comprises numerous vertical tubes h of small diameter in which the liquid rises, and a few tubes d , of larger diameter favorably placed in each section, to act as downcomers instead of the large central downcomer D of the steam belt H.

The steam belt H' is divided into cylin-

drical sectors by thin vertical plates V' , V^2 , V^3 , V^4 extending from the tube sheet f' to 65 the tube sheet f^o , and from the inner wall of the annular belt to a central exhaust pipe T, which is provided with openings t , t' , and t^2 for each sector, with an escape passage t^3 . This pipe T serves as an eduction pipe from 70 the effect for condensate, for incondensable gases, and, when robbing the effect of considerable steam. What is meant by robbing the effect will be hereinafter explained. Similar radial plates corresponding to V' to V^4 75 should of course be provided on the opposite side of the apparatus.

The inner wall of the annular belt H' is perforated opposite each sector by one or more horizontal openings S, S, the principal ones being below the level of the liquid maintained in the effect, as the most intense circulation is obtained in a tube by applying heat as near the bottom of the tube 80 as possible.

The operation of the steam belt H' is as follows:

The pressure in the eduction tube T, being low, steam will tend to enter each section from the annular chamber h^o . The 90 major steam current will be strong and low down and will induce a high liquid current in the tubes. A very large number of tubes are affected by this current in each sector.

Losing heat the steam decreases in volume. 95 However, in its passage to the central exhaust pipe T, the vertical cross section of the steam path rapidly decreases, so that that steam velocity perpendicular to the tubes is substantially maintained. The construction 100 calls for a short, direct and almost radial movement of the steam, incondensable gases, and condensate to the exit t^3 , where they can be separated and sent to heaters, other effects, or to sweetwater pumps.

The upper part of the liquid tubes is filled with steam which absorbs heat slowly. It is well to have some steam sweep the upper part of the tubes to carry incondensable gases to the exit as well as evaporate the liquid 110 film clinging to the inside of the tubes.

Since steam at low pressure contains almost as much heat as steam at high pressure, it is economical to heat cold liquids with low pressure steam, and so reduce the 115 amount of high pressure steam used; thus instead of allowing all the steam leaving an effect to pass to the next effect, it is possible to switch a part of the steam to a heater of cold liquids, or to apply it to other service that can be performed by steam at low pressure. This is called "robbing" the effect, and is common in beet sugar factories.

In robbing an ordinary standard effect, the steam is removed before it enters the effect. 125 In the new construction, it would be taken off

after it had passed through the effect, and by so doing it increases the efficiency of the heating surface by increasing the velocity of the steam past the heating surface of the 5 tubes.

By varying the width of the horizontal slots S, each section may be caused to receive practically the same amount of steam; this is not true of the vertical slots shown 10 in the prior art.

To sum up. This construction will cause high grade steam to impinge on more tubes and on that part of each tube that will induce the highest velocity of the liquid in the 15 tube. Further the condensate and incondensable gases are not allowed to remain in the heating chamber, but are swept in a short direct path to the exit.

While the drawings and description refer 20 to cylindrical effects, the improvements are applicable to multiple effects and vacuum pans of any shape where vertical are inclined tubes between tube-sheets are used, with the heating medium in the intertubular 25 space. The annular belt may be replaced by conduits of steam, and the single central exit for all sectors may be replaced by an exit for each sector or wedge especially when 30 vessels of rectangular or approximately rectangular steam belts are used.

It will also be obvious that various other modifications might be made in the herein-described apparatus, and in the construction, combination and arrangement of parts, 35 which could be used without departing from the spirit of my invention; and I do not mean to limit the invention to such details except as pointed out in the claims.

I have used in the claims the term "radial plate" referring to the partition plates V¹ to V⁴, which in a cylindrical evaporator would preferably be radial; in an evaporator of a polygonal shape these plates would be diagonally disposed, and not true radii; 45 but I mean to cover such alternative construction in the term "radial plates" aforesaid.

Having thus described my invention, what I claim and desire to secure by Letters 50 Patent of the United States is:—

1. A vacuum pan or effect provided with a steam belt having transverse tube sheets, tubes for the passage of liquid, connecting said tube sheets and opening therethrough; 55 a series of radial partition plates separating the heating space into a series of wedge shaped chambers, each containing a group of said tubes, means for supplying steam to the outer portions of said chambers, and 60 means for carrying off the heating fluid from the contracted inner portions of said chambers.

2. A vacuum pan or effect provided with a steam belt having transverse tube sheets, a

series of groups of tubes, each group consisting of small tubes for the passage of liquid upwards, and of larger tubes for the flow of liquid downwards, connecting said tube sheets and opening therethrough, a series of radial partition plates separating the heating space into a series of wedge shaped chambers, each containing a group of said tubes, means for supplying steam to the outer portions of said chambers, and means for carrying off the heating fluid from the 70 contracted inner portions of said chambers.

3. A vacuum pan or effect provided with a steam belt having a series of circumferentially arranged ports for the admission of steam, transverse tube sheets above and below said ports, tubes for the passage of liquid connecting said tube sheets and opening therethrough, a series of radial partition plates separating the heating space into a series of wedge shaped chambers, each containing a group of said tubes, means for supplying steam to said ports and through them to the outer portions of said chambers, and means for carrying off the heating fluid from the contracted inner portions of said 80 chambers.

4. A vacuum pan or effect provided with a steam belt having a series of circumferentially arranged ports for the admission of steam, transverse tube sheets above and below said ports, tubes for the passage of liquid connecting said tube sheets and opening therethrough, a series of radial partition plates separating the heating space into a series of wedge shaped chambers, each containing a group of said tubes, means for supplying steam to said ports and through them to the outer portions of said chambers, a central exhaust pipe with ports opening into the various chambers for carrying off the 90 heating fluid from the contracted inner portions of said chambers.

5. A vacuum pan or effect provided with a steam belt having a series of circumferentially arranged ports for the admission of steam, transverse tube sheets above and below said ports, tubes for the passage of liquid connecting said tube sheets and opening therethrough, a series of radial partition plates separating the heating space into a 100 series of wedge shaped chambers, each containing a group of said tubes, an annular hollow chamber surrounding said ports, means for supplying steam to said hollow chamber and through it to the outer portions 110 of said wedge shaped chambers, and means for carrying off the heating fluid from the contracted inner portions of said chambers.

6. A vacuum pan or effect provided with a steam belt having transverse tube sheets, tubes for the passage of liquid connecting said tube sheets and opening therethrough, a series of radial partition plates separating

the heating space into a series of wedge shaped chambers, each containing a group of said tubes, means for supplying steam to the outer portions of said chambers, and 5 a central exhaust pipe with ports opening into the various chambers for carrying off the heating fluid from the contracted inner portions of said chambers.

7. A vacuum pan or effect provided with 10 a steam belt having transverse tube sheets, a series of groups of tubes, each group consisting of small tubes for the passage of liquid upwards, and of larger tubes for the flow of liquid downwards, connecting said 15 tube sheets and opening therethrough, a series of radial partition plates separating the heating space into a series of wedge shaped chambers, each containing a group of said tubes, means for supplying steam to the 20 outer portions of said chambers, and a central exhaust pipe with ports opening into the various chambers for carrying off the heating fluid from the contracted inner portions of said chambers.
- 25 8. A vacuum pan or effect provided with a steam belt having a series of circumferentially arranged ports for the admission of steam, transverse tube sheets above and below said ports, tubes for the passage of liquid 30 connecting said tube sheets and opening therethrough, a series of radial partition plates separating heating space into a series of wedge shaped chambers, each containing a group of said tubes, means for supplying 35 steam to said ports and through them to the outer portions of said chambers, and a central exhaust pipe with ports opening into the various chambers for carrying off the heating fluid from the contracted inner portions 40 of said chambers.

9. A vacuum pan or effect provided with a steam belt having a series of circumferentially arranged ports for the admission of steam, transverse tube sheets above and below said ports, a series of groups of tubes, 45 each group consisting of small tubes for the passage of liquid upwards, and of larger tubes for the flow of liquid downwards, connecting said tube sheets and opening therethrough, a series of radial partition plates separating the heating space into a series of wedge shaped chambers, each containing a group of said tubes, means for supplying steam to said ports and through them to the outer portions of said chambers, and a central exhaust pipe with ports opening into the various chambers for carrying off the heating fluid from the contracted inner portions of said chambers.

10. A vacuum pan or effect provided with 60 a steam belt having a series of circumferentially arranged ports for the admission of steam, transverse tube sheets above and below said ports, tubes for the passage of liquid connecting said tube sheets and opening 65 therethrough, a series of radial partition plates separating the heating space into a series of wedge shaped chambers, each containing a group of said tubes, an annular hollow chamber surrounding said ports, 70 means for supplying steam to said hollow chamber and through it to the outer portions of said wedge shaped chambers, and a central exhaust pipe with ports opening into the various chambers for carrying off the 75 heating fluid from the contracted inner portions of said chambers.

WILLIAM H. P. CREIGHTON.
